UNITED STATES PATENT OFFICE

2,604,846

TICKET PRINTING MACHINE

Gustav Robert Ahlstrand and Karl Ake Lagerkvist, Stockholm, Sweden

Application May 28, 1947, Serial No. 751,100
In Sweden July 18, 1944Section 1, Public Law 690, August 8, 1946
Patent expires July 18, 1964

9 Claims. (Cl. 101—66)

1

This invention relates to improvements in ticket printing machines of the kind that are intended for use at railway stations or the like where a great many tickets of various prices are sold, and the present application is a continuation-in-part of application Serial No. 591,792 filed May 3, 1945, and now abandoned.

It is the chief object of this invention to provide an improved electrically driven machine which is capable of printing and issuing a great many various tickets and of accounting for the same in one single operation.

A further essential object of the invention is to provide a machine which is of a comparatively small size and yet capable of printing a great many various tickets.

It is a further object of the invention to provide a machine which is easily adjusted and operated.

A further object of the invention is to provide means that make it possible to use any adding machine to account for the tickets printed and issued by the machine.

Still another object of the invention is to provide means for preventing any false operation of the machine.

A further object of the invention is to provide means for operating the machine by hand, should the electric motor become inoperative or the electric current for driving the same break.

A further object of the invention is to provide an adjustable colour feeding device which automatically supplies the colour rollers of the machine with printing colours.

These and other objects will be set forth in the following description, reference being had therein to the accompanying drawings. Of said drawings:

Figs. 1, 2 and 3 are diagrammatical views of the machine seen from the left, from behind and from above, respectively. In these figures the essential elements of the machine and their positions relatively to one another are clearly shown.

Fig. 4 is a left side view showing the essential structure of the machine frame and part of the magazine adjusting device.

Fig. 44 is a section on line a—a of Fig. 42.

Fig. 45 is an end view of the ticket strip casing partly in section.

Fig. 46 is a side view of the ticket strip casing. Fig. 47 is a front view of the clerks' lock and of the lock connected with the means for effecting a reading off or a zeroizing of the counter.

Fig. 48 is a top view of the same elements.

Fig. 49 is a side view of the lock connected with the means for effecting a reading off or a zeroizing of the counter.

Fig. 50 is a view of the clerks' lock.

Fig. 51 is a top plan view of a simplified embodiment of the machine with one magazine.

In order to facilitate an understanding of the detailed description to follow a brief summary of the essential elements of our machine and their various functions will be given hereinafter.

Thus, our machine comprises two magazines which are movable up and down in such manner that they are counter-balancing each other. The magazines are adjusted by means of a hand wheel which can be locked in a great many positions, in the preferred embodiment to be described one hundred positions. This means that the magazines are also lockable in one hundred different positions. In each magazine there are provided a plurality of arms, printing arms, which are all pivoted on a common vertical shaft. On its underside each printing arm carries a printing plate for printing a ticket. The number of printing arms in each magazine corresponds to the number of positions into which the magazines can be adjusted. Before printing a ticket that arm which carries the corresponding printing plate must be brought to a "ready position" from where it can be rocked partly out of the magazine to a printing position immediately above a ticket strip coming from a cardboard roll mounted in a casting at the top of the machine. The printing is effected by a movable pressure table pressing the ticket strip against the printing plate at the moment assuming operative position above the ticket strip. After the printing operation has been performed a feeding device advances the ticket strip a distance corresponding to the length of the ticket. A cutting mechanism then cuts off the printed ticket which is delivered through an opening in the machine casing. The abovementioned printing arms are brought to their respective "ready positions" by adjusting the magazines by means of the hand wheel previously mentioned. There will always be two printing arms in "ready position" at a time, one in each magazine, but a special selecting device makes it possible to ensure on beforehand that the correct arm will be brought into printing position at the working stroke of the machine.

Another important element of our machine is the counter which accounts for the tickets sold by the operator. The construction of the counter, however, forms no part of our invention. On the contrary, it is an essential feature of the invention that we use no counting device specially designed for our machine. At the free ends of the printing arms we have provided special means of a very simple construction which make it possible to use as a counter any adding machine provided with a control strip on which amounts entered in the machine as well as totals are printed. When our ticket printing machine performs a working stroke and the selected printing plate is advanced into its operative position the said special means cooperate with the setting members of the adding machine in such manner that the value of the ticket to be printed and issued is entered in the adding machine and printed on the control strip. As will be explained later any-

body skilled in the art should be capable of designing the simple elements for connecting the special means on the printing arms with the setting members of such adding machine as he may prefer to use as a counter.

Our machine, of course, comprises a great many other elements than those now indicated. The construction and operation of these elements, however, will be clear from the following detailed description.

Frame work

The essential structure of the frame work of the machine is clear from Figs. 4-6. For the sake of simplicity reference character 1 is used to indicate parts of the frame work wherever such are shown in the drawings.

Main shaft

The main shaft is indicated by reference character 2. During a working stroke of the machine the main shaft makes one complete revolution, a plurality of cams mounted on the same imparting various movements to the elements of the machine, see Fig. 2. Each group of elements cooperating for a certain common purpose and receiving their movements from a common cam on the main shaft will be described in a separate paragraph.

Drive shaft

The main shaft 2 receives its rotation from a drive shaft 3, see Fig. 1, the two shafts being connected with each other by means of a coupling to be described later. The drive shaft 3 is driven by an electric motor 4, which is indicated in dot and dash lines in Fig. 1. This motor and the coupling connecting the same to the drive shaft 3 may be of any suitable type and forms no part of the invention.

Magazines and printing arms

The construction of the magazines is best shown in Figs. 4-6. Each magazine consists of two plates of similar shape, a top plate 5 and a bottom plate 6. To reduce its weight each such plate is provided with an opening 7. The top plate 5 and the bottom plate 6 of each magazine are connected to each other by a rear wall 8, see Fig. 4.

As will be described more clearly later the two magazines are movable in the vertical direction in such manner that they counterbalance each other. Each magazine is guided by a vertical rail 9 of rectangular cross section as well as by a rod 10 of circular cross section. At both ends the rails 9 as well as the rods 10 are fixed to the machine frame. Each rail 9 engages in recesses 11 provided in two small plates 12, one fixed to the top plate 5 and the other to the bottom plate 6 of the respective magazine. The plates 12 are made of a special material with a low frictional resistance. Each rod 10 is intended for cooperation with four rollers 13, two of which are mounted in a frame construction 14 fixed to the top of the corresponding magazine (see Fig. 5), the other two rollers being mounted in the same manner at the bottom of the magazine. The said rollers ensure a low frictional resistance when the magazines are being adjusted into their various positions.

On a vertical shaft 15 extending between and fixed to the top plate 5 and the bottom plate 6 of the respective magazine there are pivoted one hundred arms 16, just a few of which, however, are shown on the drawings. As will be seen from Fig. 7, which shows an arm 16 viewed from below, each arm carries a printing plate 17 which is

intended for printing a ticket. Each printing arm 16 consists of an arch-shaped portion carrying the printing plate and a straight portion, the latter at its free end provided with an aperture 18 for the shaft 15 and formed with a nose with a lateral recess 19. The purpose of the recess 19 will be explained in connection with the description of the magazine selecting device. The turning point of the printing arms 16, i. e. the shaft 15, coincides with the centre of the arch-shaped portions of the arms. Reference character 20 indicates frictional surfaces on the printing plates which are intended to cause a colour roller, over and against which the printing plates are passing when being advanced into printing position, to start rotating before the printing plate itself contacts with the colour roller. This colouring of the printing plates, however, will be described more specifically later.

At its free end each printing arm 16 carries a plate 21, the recessed front edge of which is adapted to cooperate with the counter in a manner which will be described later.

To prevent the printing arms 16 from rebounding after they have reached operative position each arm is provided with a lateral recess 22 which, in the very moment of the arm reaching its operative position, is entered by a locking pin. Finally, near its free end each printing arm 16 is provided with an aperture 23 which is intended to be engaged by a locking pin on the above-mentioned movable pressure table. These locking pins will be described in connection with the elements actuating the same.

It will be understood that a printing arm 16 must be partly rocked out of the magazine into an operative position before a ticket can be printed by the printing plate carried by the arm. In this position of the arm the printing plate carried by the same is situated close above the ticket strip 24, which is pressed against the printing plate during the working stroke of the machine, see Fig. 3. It might be well to state here that the printing position is the same for all printing arms 16 irrespective of to which magazine they belong.

Magazine selecting device and means for actuating printing arms

As will be understood from the above description the printing arm 16 corresponding to the ticket to be printed must be brought to a "ready position" from where it can be moved into printing position. This is obtained by adjusting the magazines which, as will be recalled, are movable in the vertical direction. However, since there are two magazines there will always be two printing arms 16 at a time assuming "ready position." Thus, it will be necessary before starting the working stroke of the machine to arrange that the correct printing arm 16 will be brought to the printing position during the working stroke. To this end there is provided a special magazine selecting device which makes it possible to decide on beforehand, from which magazine a printing arm 16 is to be moved into printing position.

The magazine selecting device, which is shown in Figs. 8-10, comprises a handle 25 connected with one leg of a U-shaped lever 26. Said lever is loosely mounted with its free ends on a shaft 27 journalled in two vertical portions of the frame 1. A link 28 connects the lever 26 with a slide 29, a slot 30 in the latter being engaged by two pins 31 fixed to the frame. The slide 29

is formed with a lateral projection 32, an oblique slot 33 in the same being engaged by a pin 34 fast on a shaft 35. Said shaft is loosely mounted in the previously mentioned vertical portions of the frame 1 and slideable in its longitudinal direction. At each end the shaft 35 carries a downwardly extending member 36 at its lower end formed with a lateral projection 37 which is bifurcated to engage in a groove cut in a pin 38. The pins 38 are loosely mounted in the upper ends of two arms 39 which are fast on a common shaft 40 supported in the machine frame 1. The upper ends of the arms 39 are bent in U-shape when seen from above, the pins 38 projecting through apertures in the legs of the U. Fast on the shaft 40 is also a one-armed lever 41 at its free end carrying a roller 42. A spring 43 mounted around the shaft 40 between one of the abovementioned portions of the frame 1 and one of the arms 39 urges the roller 42 to engage on a cam 44 fast on the main shaft 2. From the shape of the cam 44 it will appear that the same, when rotated during the working stroke of the machine, will impart a reciprocating movement to the shaft 40, the arms 39 thereby being first rocked in one direction and then back to the initial position. As will appear from the following description this movement of the arms 39 will cause a printing arm 16 to advance from its magazine into printing position and, towards the end of the working stroke, to turn back again into the magazine.

From what has been said above it will be understood that a turning of the handle 25 in one direction or the other will cause the shaft 35 to slide correspondingly axially in its longitudinal direction. At such movement the bifurcated lower ends of the downwardly extending members 36 engaging with the pins 38 will cause the latter to participate in the movement of the shaft 35.

Each of the pins 38 is adapted to cooperate with a slide 45, see Figs. 8-14. Each of said slides is mounted in a track 46 cut in a guide member 47 which is fixed to the same vertical portions of the frame 1 that support the above-mentioned shafts 27 and 35. In each guide member 47 there is cut a slot 48 through which projects a U-shaped member 49 at the base fixed to the slide 45. Said U-shaped members 49 are adapted to be engaged by the pins 38, which, however, are kept at such distance from each other by the members 36 extending from the slideable shaft 35 that only one pin 38 at a time can engage between the legs of the corresponding U-shaped member 49. In other words, when the shaft 35 is caused to slide in one direction or the other one of the pins 38 is moved into engagement with the corresponding member 49 while the other pin 38 is moved out of its previous engagement with the corresponding member 49. As seen from the drawing the slides 45 consist of a broader portion fitting into the track 46 and a narrower portion. To the latter is fixed a small projection 50. The said projections always engage the recesses 19 of those two printing arms 16 which, one in each magazine, at the moment are in alignment with the projections 50, i. e. which at the moment assume "ready positions."

It will be clear that the reciprocating rocking movement of the arms 39 as described above, will cause that slide 45 which at the moment is engaged by a pin 38 to perform a reciprocating longitudinal movement, at which the printing arm 16 engaged by the projection 50 of the said slide will be moved out into printing position and back again. Thus, by turning the handle 25 it is

possible to select on beforehand that magazine from which a printing arm 16 is to be advanced into printing position.

It is desirable, of course, that those printing arms 16 which do not assume "ready position" shall not be able to leave their rest positions in the magazines. To this end there is provided a rail 51 of angular shape fixed to the machine frame. All printing arms 16 not assuming "ready positions" are prevented by this rail to move out of the magazines. For the printing arms 16 assuming "ready positions," however, there are provided recesses in the edges of the rail 51 through which the selected printing arm 16 passes when being moved into printing position.

For securing in its inactive position that slide 45 which is not engaged by a pin 38 and, consequently, the printing arm 16 not selected, the following means are provided, see Figs. 11-14. On one leg of each U-shaped member 49 there is pivotally mounted a two-armed lever 52, one arm of which carries a small plate 53. The other arm of the lever 52 is formed with a projection 54 which is adapted to cooperate with a recess 55 cut in the edge of a small plate 56 fixed to the guide 47. A spring 57 compressed between the bottom of a recess 58 cut in the bottom of the U-shaped member 49 and the plate 53 constantly urges the projection 54 of the lever 52 to engage the recess 55. However, when a pin 38 enters between the legs of the U-shaped member 49 associated with one of the slides 45, i. e. when one of the magazines is being selected, the lever 52 mounted on said member 49 is rocked by the pin 38 to disengage the recess 55, the slide 45 being thus free to move a printing arm 16 into printing position.

Magazine adjusting device

After that magazine has been selected which contains the printing arm 16 to be used for printing the desired ticket said arm must be brought to its "ready position." For such purpose the following means are provided.

A hand wheel 59 is mounted on the shaft 27 journaled in the machine frame 1, see Figs. 4-6. Fast on the same shaft are two indicator drums 60, each drum on its circumference carrying the names of the stations for which tickets can be printed by the printing arms 16 contained in the corresponding magazine. Part of each drum is visible through an opening in the machine casing. Two screens 61 Fig. 10 carried by arms 61 fixed to the shaft 27 are so arranged that only one indicator drum can be observed at a time through the corresponding opening in the machine casing, said drum being of course that which corresponds to the selected magazine. A gear 63 fast on the shaft 27 meshes with a gear 64 fixed to one end of a shaft 65 extending perpendicularly to the shaft 27 and journaled at one end in a conical base plate 66 fixed to the machine frame and at its other end in a cross bar 67 fixed to the vertical walls of the frame 1 which support the shaft 27. Another gear 68 fixed to the opposite end of the shaft 65 meshes with two toothed racks 69, each of which is fixed to one of the magazines. Thus, when the hand wheel 59 is turned in one direction or the other the magazines are caused to move along the rods 10 and the rails 9 as mentioned above. It will be understood that, when the name of that station for which a ticket is to be printed is visible through the corresponding opening in the machine casing, that printing arm

16 which carries the corresponding printing plate has been adjusted into its "ready position."

It is obvious that the machine might be damaged if the hand wheel 59 were fast on the shaft 27. In such case a continued actuation of the wheel after the magazines having reached their end positions would seriously injure the adjusting elements above described. For the purpose of preventing such accident the wheel 59 is not rigidly secured to the shaft 27. A hub 70 connected with the outer wheel 59 by means of spokes 71, only one of which is visible in Fig. 6, is loosely mounted on the shaft 27. By means of a nut 72 the hub 70 can be tightened against an annular flange 73 formed on the shaft 27. The nut 72 is screwed on to the threaded end of the shaft 27 and can be locked in its adjusted position by means of a locking screw 74. Thus, the friction between the wheel hub 70 and the flange 73 of the shaft 27 can be so adjusted that the grip between the wheel 59 and the shaft 27 loosens as soon as attempt is made to continue turning the wheel 59 after the magazines have reached their end positions.

It is of importance that the magazines are adjusted into exact positions and locked there. To this end the hand wheel 59 is constructed in the following manner. A sleeve 75 at one end carrying a disc 76 is displaceably but not turnably mounted on the shaft 27 of the hand wheel 59. A spring 77 mounted around the shaft 27 and compressed between the end of the sleeve 75 and the adjacent indicator drum 60 is constantly pressing the disc 76 towards the wheel 59. An upstanding flange 78 on the disc 76 is formed with recesses 79, which may be said to correspond to the various positions into which the magazines can be adjusted. The hand wheel 59 is provided with a groove in which a ring 80 is mounted. The ring 80 rests on upstanding end portions of three levers 81, the other ends of which extend towards the shaft 27, a flattened end portion 82 of the spring actuated sleeve 75 pressing the said levers 81 against the hub 70. The ring 80, when unactuated, does not reach the bottom of the groove provided in the outer wheel 59. Thus, when the ring is impressed, the levers 81 cause the sleeve 75 and the disc 76 to move inwards against the action of the spring 77. The recesses 79 of the disc 76 are adapted to cooperate with a pin 83 mounted in a recess cut in a stud 84 which is fixed to the machine frame 1, the spring 77 urging the recesses 79 to engage with said pin 83. As long as such engagement is unbroken the shaft 27 cannot be rotated and no adjustment of the magazines can take place. Upon impressing the ring 80, however, the levers 81 will cause the disc 76 to disengage the pin 83, the shaft 27 being now free to turn.

Magazine locking device

To keep the magazines in their exact positions during the working stroke of the machine the following means are provided, see Figs. 15 and 16.

At its one end a two-armed lever 84 of angular shape mounted on a shaft 85 carries a roller 86 which is urged by a spring 87 extending between the lever and the machine frame 1 to bear against a cam 88 mounted on the main shaft 2. At its other end the lever 84 is turnably connected with one end of a link 89, the other end of which is bent at 90° and pivoted to a one-armed lever 90 fixed to a vertical shaft 91. At its upper end the shaft 91, which is journaled at both ends 75 in the frame 1, carries a body 92 of cylindrical

shape having a plurality of flanges 93. These flanges are adapted to engage with corresponding recesses 94 formed between flanges on the back wall of one of the magazines, see also Fig. 5. The flange body 92 is eccentrically mounted on the shaft 91 and thus a turning of the shaft will cause the flanges 93 to engage or disengage the corresponding recesses 94 of the said magazine. It will be clear that the turning movement of the shaft 91 is caused by a rotation of the main shaft 2 with the cam 88 thereon. Before a working stroke of the machine begins, the cam 88 assumes such position that the roller 86 engages in the recess 95 cut in the cam surface, in which position of the lever and link system 84, 89, 90 the flange body 92 is out of engagement with the back wall of the said magazine. Immediately after the working stroke of the machine has begun the roller 86 is moved out of engagement with the recess 95 of the cam 88, the movement thus imparted to the lever 84 causing the shaft 91 to turn the flanges 93 into engagement with the back wall of the magazine. As will be clear from the shape of the cam 88 this engagement is maintained during practically the whole working stroke, the said magazine as well as the other being thus effectively locked in the adjusted positions. At the end of the working stroke the roller 86 again enters into the recess 95, the rocking movement thereby imparted to the lever 84 causing the flange body 92 to disengage the back wall of the said magazine.

Means for preventing printing arms from rebounding

The printing arms 16 advance into printing position at a considerable speed. To prevent any tendency of the said arms of rebounding after having arrived into operative position, there are provided the following special means, see Figs. 26-28. As is shown in Fig. 7 each printing arm 16 is provided with a recess 22 cut in the outer edge of the arch-shaped portion of the arm. When a printing arm 16 advances out of a magazine it strikes with its outer edge against a pin 161 which is fast on a lever 162 mounted on a vertical shaft 163. Said shaft is journalled in two plates 164 and 165 projecting from the vertical rail 51 previously mentioned. The pin 161, which is thus movable along a circular path, when contacted by the advancing printing arm 16 is moved somewhat outwards by the same. It will be recalled that the printing arms 16 when advancing into printing position pass through recesses cut in the edges of the angular rail 51. Said recesses are indicated by reference character 166, see Figs. 26 and 27. It is obvious that an arm 16 from one of the magazines will move the pin 161 in one direction while an arm from the other magazine will actuate the pin in the opposite direction. During the continued progress of the printing arm 16 the pin 161 glides along the outer edge of the arm until the recess 22 of the latter arrives at the pin. In this moment the arm has reached its printing position, a rebounding of the arm being prevented by the pin 161 snapping into the recess 22. The spring force necessary for causing the pin 161 to enter the recess 22 is received from a spring 167 which extends between the free ends of two levers 168 pivoted on the plate 165. Through an arch-shaped slot 169 cut in the plate 165 there projects from below a pin 170 fast on a lever 171 which is fixed to the vertical shaft 163. The levers 168, which are urged towards each other by the spring 167, strive to keep the

pin 170 at the middle point of the slot 169. In this position of the elements the pin 161 is situated in the path of movement of any printing arm 16 which will advance into printing position irrespective of to which magazine the said arm belongs.

However, before the printing arm 16 advanced into printing position can be restored to its initial position in the respective magazine the pin 161 must be caused to disengage the recess 22 of the said printing arm. To this end there is provided an angularly bent member 172, at one end fixed to a fork member 173 and at its other free end formed with two oblique edges 174, see Figs. 26 and 28. The latter are adapted to cooperate with a projection 175 extending downwardly from the lever 171. The fork member 173 carries a roller 176 which is caused by a spring 177 mounted around a rod 178 fixed to the fork member and slidably mounted in the rail 51 to engage on a cam 179 fast on the main shaft 2. The fork-shaped end of the member 173 embraces the main shaft 2 and serves to guide the longitudinal movement of the fork member. The shape of the cam 179 is such that the fork member 173 is held in the position shown in Figs. 26 and 28 during the essential part of the working stroke of the machine. However, towards the end of the working stroke, when the pin 161 is to be removed from its engagement with the recess 22, the cam 179 allows the fork member 173 to slide towards the main shaft 2. At such movement of the fork member one of the oblique edges 174 of the bent member 172 strikes against the projection 175 attached to the lever 171. In rest position of the elements this projection 175 is situated right opposite the free end of the bent member 172 but when the pin 161 is in engagement with a printing arm 16 the said projection is moved a little to one side or the other so that one of the oblique edges 174 will strike against the projection 175 when the fork member 173 is displaced as above mentioned. At such contact between the projection 175 and one of the oblique edges 174 the pin 161, which has already been moved out of its rest position by the printing arm 16 at the moment assuming operative position, is moved somewhat further in the same direction, i. e. the pin 161 leaves the recess 22 of the said printing arm 16, the latter being thus free to return to its magazine. From the foregoing description it will be clear that when a printing arm 16 from one magazine assumes printing position the lever 162 with the pin 161 fast thereon as well as the lever 171 carrying the projection 175 have been rocked in one direction. When a printing arm belonging to the other magazine is being advanced into operative position the pin 161 and the projection 175 will be rocked in the opposite direction. Finally, immediately before the end of the working stroke of the machine the various elements are restored to the positions shown in Figs. 26 and 28.

The pressure table

It has been mentioned above that the printing plate selected for printing a ticket must be brought into a printing position right above the ticket strip. It has also been explained by what means the arm 16 carrying the printing plate in question is advanced into such position. The printing is then effected by the ticket strip being pressed against the printing plate. For this purpose the following means are provided, see Figs. 1 and 17. Carried in a guide 96 fixed to the machine frame 1 is a slide 97 which widens at

the top to a table 98. This table, the pressure table, is constantly urged downwards by means of two springs 99 which extend between pins 100 fast on the pressure table and screws 101 by means of which the guide 96 is fixed to the machine frame. At its lower end the slide 97 carries a roller 102 adapted to cooperate with a cam 103 fast on the main shaft 2. Upon rotation of the main shaft 2 the cam 103 will apparently cause the slide 97 with the pressure table 98 thereon to move upwards. When reaching its uppermost position, which is shown in Fig. 17, the pressure table 98 presses the ticket strip against the printing plate advanced in printing position as well as against two rollers, one belonging to a mechanism for printing consecutive numbers and the other forming part of a mechanism for printing the date of sale, see Figs. 1 and 2. As will be explained in detail later the consecutive number printing mechanism and the date printing mechanism are so located relative to the printing position of the printing plates that the ticket strip, when arriving into printing position beneath the printing plate, has already been provided with a consecutive number and an indication of date.

Right above the operative position of the printing plates 17 there is fixed to the machine frame 1 a stationary plate 104 which prevents the arm 16 advanced into operative position from being bent upwards when contacted by the pressure table (see Fig. 2).

The upward movement of the pressure table will also cause a pin 105 fast on a projection integral with the pressure table to enter into the aperture 23 of that printing arm 16 which at the moment assumes printing position. From the shape of the cam 103 it will be clear that the pressure table presses the ticket strip against the printing plate and the other printing mechanisms above mentioned only for a brief moment. However, the pressure table does not return immediately to its initial position but during an essential part of the working stroke it assumes an intermediary position in which the pin 105 still engages the aperture 23 of the printing arm 16. Thus, the latter is effectively locked until the pressure table definitely returns into its original position. As will be clear from the description of the counter this extended locking of the arm 16 is of importance for the operation of the counter.

Ticket strip feeding device

At each working stroke of the machine the ticket strip 24, of course, must be advanced a distance corresponding to the length of a printed ticket. This is effected by a special feeding device of the following construction, see Figs. 1, 18 and 19.

The ticket strip 24, which, as will be described later, is formed to a roll mounted in a casing at the top of the machine, is guided by a roller 106 to enter between two feed rollers 107 and 108 which are so close to each other that a rotation of the same will advance the ticket strip correspondingly. The required rotation of the feed rollers is effected by the following means.

The feed rollers 107 and 108 are mounted on two shafts 109 and 110 respectively, which shafts are journalled in a vertical wall of the frame 1 and a plate 111 projecting from another part of the frame 1. A gear 112 fast on the upper shaft 109 constantly meshes with a gear 113 fast on the lower shaft 110. The shaft 110 carries another gear 114 which, however, is not fast on

the shaft. The gears 113 and 114 are adapted to engage each other by means of projections, together forming a claw coupling 115, so that the gear 114, when being rotated in one direction, imparts a rotation to the gear 113, while a rotation of the gear 114 in the opposite direction causes no rotation of the gear 113. A spring 116 mounted around the shaft 110 and compressed between the plate 111 and the gear 114 urges the latter towards the gear 113. The gear 114 is in constant mesh with a vertical toothed rack 117, the lower end of which meshes with a gear 118 mounted in a wall of the frame 1. The gear 118 in its turn meshes with a toothed wheel 119 fast on the main shaft 2. The wheel 119, however, is not toothed all around but only at part of its circumference. In Fig. 18 the elements now described assume their initial positions. It will be clear that a rotation of the main shaft 2 and the wheel 119 thereon will cause the toothed rack 117 to move upwards as long as the teeth of the wheel 119 mesh with those of the gear 118. At this upward movement of the rack 117 a rotation is imparted to the gear 114 loose on the shaft 110, which rotation is transferred by the claw coupling 115 to the gear 113 fast on the shaft 110. This shaft with the lower feed roller 108 fast thereon will rotate in one direction while the other shaft 109 with the upper feed roller 107 fast thereon will be rotated in the opposite direction thanks to the gear 113 meshing with the gear 112. The feed rollers, rotating in opposite directions, thus advance the ticket strip 24 entering between the rollers. The length of movement thus imparted to the ticket strip corresponds to the length of a ticket. When the gear 118 is no more meshing with the teeth of the wheel 119, the rack 117 is free to return to its initial position by its own weight, a rubber cushion 120 fixed to the lower end of the rack ensuring a smooth landing of the same on the bottom plate of the machine frame 1.

Date and consecutive number printing device

For the sake of control each ticket issued by the machine should have a number and an indication of the date of sale. It has been indicated above that the various printing plates 17 carried by the arms 16 are not used for printing consecutive numbers and dates, it being so arranged that the ticket strip 24 is also pressed by the pressure table 98 against two rollers, one carrying figures for indicating the date of sale and the other carrying figures for printing consecutive numbers. The said rollers are so located that the ticket strip 24 passes beneath the same before arriving beneath the printing position of the printing plates. Thus, that part of the ticket strip which receives printing from a printing plate has already been provided with date and consecutive number from the said rollers. In other words, a complete ticket is printed in two steps, i. e. when the printing of one ticket is being finished, the date and consecutive number of the next ticket is simultaneously printed.

For printing date and consecutive numbers the following means are provided, see Figs. 20 and 21. Two rollers 121 and 122, each consisting of a number of figure type wheels, are carried in a sledge 123 which is slidable on a guide member 124 fixed to a vertical portion of the frame 1. The roller 121 belongs to a consecutive number counter of such standard type well known in the art wherein the rocking of a lever causes an advance of one unit. The said lever is indicated by reference character 125. The roller 122

belongs to a date printing mechanism. The consecutive number counter forms no part of this invention, since any automatically operating mechanism can be applied to the machine without any inventive work being necessary. It will be apparent that the lever 125 has to be actuated at each working stroke of the machine. This actuation is obtained by the sledge 123 being moved towards a pin 126 fast on the frame 1 which pin strikes against the upper end of the lever 125, thus imparting the rocking movement to the same which causes an advance of one unit in the consecutive number counter. The sledge 123 receives its longitudinal movement by a link member 127 fixed at one end to the sledge and at the other end connected with one end of a two-armed lever 128, a pin 129 on the latter projecting through a transverse slot 130 in the link member 127. The two-armed lever 128 is pivoted on a shaft 131 journaled in the machine frame 1 and carries at its other end a roller 132 which engages with a cam 133 fast on the main shaft 2. A spring 134 extending between a pin 135 fast on the upper arm of the lever 128 and a stud 136 projecting from the frame 1 constantly urges the roller 132 to bear against the cam 133. From the shape of said cam it will be clear that a revolution of the main shaft 2 will cause the sledge 123 to move from the position shown in Fig. 21 to the left until the lever 125 contacts the pin 126. In the extreme left position of the sledge 123 the rollers 121 and 122 of the consecutive number counter and the date printing mechanism are situated close above the ticket strip 24 which is then pressed by the pressure table 98 against the said rollers, a consecutive number and the date being thus printed on the ticket strip. Towards the end of the working stroke the sledge 123 returns to its initial position (to the right in Fig. 21).

It should also be mentioned that the date printing mechanism is of a type well known in the art, the adjustment of which is effected by hand. The setting members of the date printing mechanism are indicated by reference character 137 (see Fig. 21).

While moving into printing positions the consecutive number counter and the date printing mechanism pass above and against a colour roller which supplies the types of the said mechanisms assuming printing positions with colour. The said colour roller belongs to a colouring device which will be described hereinafter.

Colouring device

Before being advanced into printing position the printing plates must be supplied with printing colour. This is effected by a system of rollers, see Figs. 22 and 23, which are mounted in two walls 138 and 139 fixed to a vertical portion of the frame 1. The colour is supplied to this system of rollers from a special feeding device which will be described later. The colour arrives through six pipes 142 to a roller 141 which is journaled in two levers 142 pivotally connected with the walls 138 and 139. Two springs 143 interposed between the levers 142 and a rail fixed to and extending between the walls 138 and 139 hold the roller 141 pressed against a second roller 144 which at a certain moment of the working stroke of the machine, is rotated, colour thereby passing from the roller 141 on to the roller 144. The latter is somewhat displaceable in the vertical direction and is controlled by two springs 145. Each spring 145 is provided in a recess in

the respective walls 138, 139 and coiled around a rod 146 which is connected with the shaft of the roller 144 and extends downward through an aperture in the lower edge of the respective wall 138, 139 as well as through an aperture in a rail 147 extending longitudinally beneath the roller 144. The rail 147 is pivotally connected with the walls 138, 139. The rods 146 are threaded at their ends and on to each there is screwed a small nut 148. Thus, the angle position of the rail 147 will determine the vertical position of the roller 144 in the walls 138, 139. The springs 145 strive to force the roller 144 upwards against two rollers 149 and 150 also mounted in the walls 138, 139, but when the machine is at rest a projection 151 fast on the slide 97 of the movable pressure table 98 and engaging with the rail 147 prevents the roller 144 from contacting with the two rollers 149 and 150, as will be clearly seen from Fig. 23. When, however, the pressure table 98 moves upwards for the purpose of pressing the ticket strip 24 against the selected printing plate 17 and the consecutive number counter and the date printing mechanism, the rail 147 is released and the springs 145 move the roller 144 into contact with the rollers 149 and 150. As has been mentioned above the roller 144 is rotated at a certain moment of the working stroke, i. e. when contacting with the rollers 149 and 150. At such rotation colours is consequently also transmitted from the roller 144 to the two rollers 149 and 150. The above described colour roller system is so located that the printing arm 16 which is being moved into printing position passes above and against the roller 149, the latter being rotated by the printing plate and thereby providing the same with colour sufficient for printing a ticket. As has been mentioned in a previous paragraph the consecutive number counter and the date printing mechanism are also situated right above the ticket strip 24 at the moment when the same is pressed upwards by the pressure table 98. When moving into such position said mechanisms pass above and against the roller 150 which supplies the figure type wheels of the said mechanisms with printing colour. The movements of the various elements now described are so adjusted that the rollers 149 and 150 have received a fresh supply of colour immediately before the selected printing plate and the consecutive number counter and the date printing mechanism contact with the said rollers.

The rotation of the roller 144, which is necessary for transmitting colour from the roller 141 to the rollers 149 and 150, is obtained by the following means. Pivoted on a lever 152 mounted on a shaft 153 journaled in the machine frame 1 is a toothed rack 154 which engages with a toothed roller 155 fixed to the shaft of the colour roller 144. The lever 152 carries a roller 156 which is urged by a spring coiled around the shaft 153 and fixed to the lever 152 and to the frame 1 to bear against a cam 157 fast on the main shaft 2. The cam 157 is of such shape that a sliding movement is imparted to the toothed rack 154, during the rotation of the main shaft 2, which movement is transmitted to the roller 144 via the toothed roller 155, both of said rollers being fast on a common shaft. As will be seen Fig. 22 a cam groove 158 is cut in the toothed roller 155, which groove is engaged by a stationary projection 159 carried by a plate 160 projecting from the wall 138. The roller 144, the shaft of which is slidable in the walls 138, 139, will thus

receive a short reciprocating longitudinal motion when the roller 155 is rotated by the toothed rack 154. Such reciprocating motion is of importance for obtaining an even distribution of the colour when transmitted from the roller 141 to the roller 144 as well as from the latter to the rollers 149 and 150.

It will be recalled that the colour roller 149 is rotated by the printing plates 17 passing over and against the same, the printing plates thereby receiving colour from the roller. It has proved, however, that the most even colouring is obtained if the roller is allowed to slide longitudinally on its shaft while being rotated. The desired sliding motion of the roller 149 is obtained by such positioning of the same that an imagined extension of the shaft of the same passes at a distance from the turning points, i. e. the shafts 15 of the arms 16, see Fig. 3. It will be clear that with such arrangement each point on the arch-shaped portions of the arms 16 will pass the colour roller 149 obliquely. When a printing plate passes over and against the roller 149 every point contacting with a point on the roller thus strives not only to rotate the roller but to move the same in the longitudinal direction on its shaft. Consequently, when an arm 16 is advanced into printing position the roller 149 is moved longitudinally towards the outer edge of the arch-shaped portion, the roller being moved back again in the opposite direction when the arm returns into its initial position in the respective magazine. However, since the printing arms 16 of one magazine will cause the roller 149 to slide in one direction, while the arms of the other magazine will impart a sliding movement to the roller in the opposite direction, it is of importance that the roller 149 is caused to assume such initial positions on its shaft as will permit the roller to be displaced as described above, irrespective of from which magazine an arm 16 will advance into printing position. For such purpose the following means are provided, see Figs. 24 and 25.

Pivoted on a pin 161 fast on a vertical portion of the frame 1 is a two-armed lever 162 at its upper end carrying a pin 163. The latter is engaged by the lower bifurcated end of an angularly bent arm 164 extending downwards from and fixed to the shaft 35, see Figs. 9 and 10. When the shaft 35 is displaced in one direction or the other for purpose of selecting magazine the lever 162 is consequently rocked correspondingly by the bifurcated end of the arm 164. To the lower end of the lever 162 there is pivoted another small two-armed lever 165, a spring 166 extending between its upper end and a stud on the lever 162 striving to hold the lever 165 in the position shown in Fig. 24. The lever 165 is adapted to cooperate with the bent end of a rod 167, engaging in a slot 168 cut in a small plate 169 fixed to the same frame portion as the lever 162. The rod 167 is slidably mounted in another frame portion extending perpendicularly from that frame portion just mentioned. To the rod 167 there are fixed two fork-shaped members 170 which engage the shaft of the roller 149 on either side of the roller, see Fig. 23. When the elements assume the positions shown in Fig. 24, with the roller 149 in its extreme left position, that magazine is selected which is situated to the left of the roller 149, see Figs. 22 and 24. When an arm 16 is advanced from and returned to the said magazine the same will thus cause the roller 149 to slide to the right and then back again. When the magazine situated to the right of the

roller 149 is selected the roller, consequently, must be moved over to its extreme right position. This adjustment of the roller is effected by the lever 162 being rocked at the displacement of the shaft 35, the smaller lever 165 on the lever 162 pushing the rod 167 with the fork members 170 thereon and, consequently, the roller 149 to the right, see Fig. 24. The displacement of the shaft 35 is of such length, however, that the lever 162 with the lever 165 thereon continues rocking for a while after the roller 149 has reached its extreme right position. This will cause the lever 165 to rock against the action of the spring 166 until the lower end of the lever 165 has passed the bent end of the rod 167. The lever 165 is then rocked back into its initial position relatively to the lever 162, the lower end of the lever 165 being now located to the right of the bent end of the rod 167. From the above description it will be clear that the lower end of the lever 165 will always assume such positions that it will be ready to move the rod 167 and the roller 149 into the correct initial positions.

Colour feeding device

The colouring device described in the foregoing paragraph is supplied with colour from a feeding device which is shown in Figs. 29 and 30. This device consists of a horizontally mounted container 171 having at one end an opening for receiving a vertical cylinder 172, the free end of which is covered by a lid 173. Through this cylinder fresh printing colour is poured into the container. In the bottom of the horizontal container 171 there are mounted six valves 174, one of which is shown in cross section in Fig. 30. Each valve 174 consists of a central boring 175 and a transverse channel 176 near the bottom of the container 171. At its lower end the central boring 175 widens, a spring 177 mounted in said widened portion of the boring forcing a ball 178 upwards against the narrower portion of the boring. The upper end of the boring 175 is entered by a small piston 179, the bent upper end of which engages and is suspended in an annular groove 180 cut in a shaft 181 extending longitudinally through the container 171. The shaft 181 is eccentrically journaled at both ends in the side walls of the container 171, as clearly seen from Fig. 30. A rotation of the shaft 181 will thus reciprocate the pistons 179 of the valves 174, through which a small quantity of colour leaves at each downward stroke of the pistons. Connected with each valve 174 is a pipe 182 which extends upwards towards the colour roller 141 on which six drops of printing colour are supplied at every downward stroke of the pistons 179. As will be described hereinafter the shaft 181 is not continuously rotated but caused at certain intervals to make half a revolution. This rotation of the shaft is effected by the following means.

A shaft 183 projects through the left wall of the container 171 and is eccentrically connected with the shaft 181. Fixed to one end of a hub 184 loose on the shaft 183 is a ratchet wheel 185. The other end of the hub 184 is eccentric in relation to the shaft 183. Fast on the shaft 183 is a cylindrical drum 186 which serves as a housing for a helical spring, not shown, one end of which is fixed to the hub 184 by means of a screw 187, the other end being fixed to the inner wall of the drum 186. Said drum is traversed by a cross bar 188 provided with an aperture 189 through which the eccentric hub 184 projects. The length of the bar 188, which is slidable in

the drum 186, is greater than the diameter of the drum, the bar thus projecting through one or both of two apertures 190 in the wall of the drum. The bar 188 is intended for cooperation with two upstanding projections 191 fixed to the end wall of the container 171. The above mentioned spring mounted in the drum 186 strives to turn the same and the shaft 183 but is prevented from doing so as long as the bar 188 engages with one of the projections 191, see Fig. 30. However, when the hub 184 is turned in a manner to be described later the eccentricity of its end portion cooperating with the aperture 189 of the bar 188 causes the same to slide out of engagement with one of the projections 191, the drum being thereby released for a short moment. The spring mounted in the drum, which has been tensioned at the turning of the hub 184, now causes the drum and the shafts 183 and 181 to make one half revolution, the drum being prevented from continuing its rotation thereby that that end of the bar 188 which was released from its engagement with one of the projections 191 strikes against the other of the said projections. When the hub 184 has made half a revolution from the position shown in Fig. 30 the bar 188 will just have slid out of engagement with the upper projection 191 but when the drum 186 is caused by the above mentioned spring to make its half revolution the eccentric portion of the hub 184 forces the bar back into its previous position in the drum, the bar now striking against the lower projection 191 where it is kept locked until hub 184 has made another half revolution.

From the foregoing description it will be clear that the shaft 181 in the container 171 is caused to make half a revolution at a time and that such rotation is imparted to the shaft quite suddenly and with great force. Every second time the shaft 181 is actuated in the manner above described the pistons 179 of the valves 174 force a small quantity of colour out through the valves and through the pipes 183 on to the roller 141 of the colouring device.

The hub 184 with its eccentric portion is rotated by the step wheel 185 fast thereon, said wheel being advanced one or more steps at a time by a pawl 192 pivoted to one leg of a U-shaped lever 193. The said U-shaped lever is loosely mounted with one leg on the left end of the shaft 183 and with its other leg on a screw 194 projecting through the right end wall of the container 171 and recessed in its end to receive the eccentric end of the shaft 181, see Fig. 30. As will be seen from Fig. 29 the colour container 171 is located quite near the pressure table 97, 98, two arms 195 fixed to the guide 96 for the pressure table supporting the container. Every time the pressure table raises as previously described an angularly bent member 196 fixed to the slide 97 of the pressure table strikes against the middle portion of the U-shaped lever 193, the pawl thereby advancing the step wheel 185 correspondingly. When the pressure table returns to its initial position the lever 193 falls back by gravity until it strikes with its one leg against one end of a two-armed lever 197. The latter, which is arch-shaped to follow the contour of the container 171, is pivotally mounted on a pin 198 fixed to the right end wall of the container. Through an aperture in the other end of the lever 197 there projects a pin 199 fast on a small disc 200. A spring, not shown, strives to force the said pin into engagement with one of a plurality of recesses 201 made in the end wall

of the container 171. The arrangement now described thus makes it possible to lock the lever 197 in various positions relatively to the end wall of the container. The position of the lever 197 in its turn will determine the initial position from which the lever 193 is rocked each time the member 195 fast on the pressure table strikes against the same. As will be seen from Fig. 29 the initial position of the lever 193 will determine the length of movement imparted to the same by the raising pressure table and, consequently, the size of the turning motion imparted to the step wheel 185. In other words, by adjusting the lever 197 it is possible to vary the intervals at which the shaft 181 is rotated and, thus, to adjust the supply of colour to the colour rollers described in the foregoing paragraph.

Ticket strip cutting mechanism

20 It has been described above how the ticket strip is advanced beneath the printing plate 17 assuming operative position and how the strip is pressed against the same by the movable pressure table 98. It will also be recalled that the ticket strip when receiving prints from a printing plate is already provided with consecutive number and date, said indications having been printed during the foregoing working stroke. After the printing of a ticket has been completed the ticket strip must be cut off and the finished ticket issued from the machine. This is effected in the following manner, see Figs. 31 and 32.

Immediately after the pressure table 98 has withdrawn from its uppermost position, in which it presses the ticket strip 24 against the printing plate 17 at the moment assuming printing position, the ticket strip feeding device above described starts operating, the ticket strip being advanced a distance corresponding to the length of a ticket. Close to the printing device there is provided a stationary knife 202 beneath which the ticket strip is advanced. To cooperate with this knife there is provided a second knife 203 the shape of which is clearly shown in Fig. 31. A pin 204 fast on the stationary knife 202 projects through a slot 205 in the knife 203, the latter being thus slidable relatively to the stationary knife 202. Near its lower bifurcated end the knife 203 carries a roller 206, which is adapted to cooperate with a cam 207 fast on the main shaft 2. A spring 208 mounted around a rod 209 and compressed between a frame portion 1 and an angular projection 210 fast on the knife 203 serves to hold the roller 206 pressed against the cam 207. As can be seen from the drawing the latter is of such shape that a rotation of the main shaft 2 will cause the knife 203 to raise. At such movement the edges of the two knives cut off the ticket strip 24 which falls right down into a funnel 211 opening into the machine casing.

Counter

As has been mentioned above the counter which accounts for the printed tickets is not specially constructed for our machine. On the contrary, it is an essential feature of our invention that almost any adding machine on the market may be used as a counter. Of course it will need some constructive work to connect another type of adding machine than that used by us with the means intended for cooperation with the same, but anyone skilled in the art will have no difficulty in designing the necessary connecting elements.

75 It may be generally said that before an add-

ing machine can be connected with our ticket printing machine all elements belonging to the key board have to be removed. In most machines there will then remain of the setting elements link members, which are adapted to perform longitudinal movements during the working stroke of the machine, the lengths of such movements determining the amount that is entered into the totalizer. The adding machine that we use as a counter belongs to this kind of machines. The general outline of the same is indicated in dot and dash lines in Fig. 1. As will be seen from this figure the counter is located right beneath the shaft 21 carrying the adjusting wheel 59 and in front of the printing position of the printing arms 16. In this adding machine we have removed all of the setting elements except the links 212, one of which is seen in Fig. 1. When this adding machine performs a working stroke said links are moved longitudinally to the right. Such movements continue until the links strike against some stop means. In the ordinary machine of this type the length of movement of each link 212 is determined by the key of the corresponding key row that has been depressed but after having been changed to suite our ticket printing machine the movements of the links 212 are determined by the recessed plates 21 attached to the free ends of the various printing arms 16. At one end each link 212 is turnably connected with a toothed segment 213 from the rotation of which the link receives its longitudinal movement. At the opposite end each link 212 is turnably connected with a two-armed lever 214. All levers 214 are loose on a common shaft 215 mounted in the machine frame 1. Upon longitudinal movements being imparted to the links 212 by rotation of the toothed segments 213 the free ends of the levers 214 will engage with the recessed edge of the plate 21 carried by the printing arm 16 at the moment assuming printing position. The toothed segments 213 are constructed to continue turning until they meet a resistance, which they do when the free ends of the levers 214 strike against the edge of the said plate 21. In our counter there are eight links 212. As will be seen from Fig. 7 the edge of a plate 21 is cut in such manner that there are formed eight small edges 216 against which the free ends of the levers 214 are caused to engage at the displacement of the links 212. From the above it will be clear that by differently cutting the edge of the plates 21 the lengths of the movements of the links 212 as well as the angle positions in which the toothed segments 213 will stop can be varied. It is the angle positions of the toothed segments 213 that finally determine the amount that will be entered into the totalizer of the adding machine. It will now be understood that a plate 21 formed with a certain combination of actuating edges 216 will cause a certain amount to be entered into the totalizer of the adding machine, i. e. the counter of our ticket printing machine. This amount, of course, corresponds to the price of the ticket which is printed by the printing arm 16 carrying the said plate 21. The same amount, however, should also be printed on a control strip. For this purpose each toothed segment 213 is turnably connected with one end of an arm 217, said arm at its other end carrying figure types. The arms 217 are intended for cooperation with a roller 218 around which the control strip 219 is advanced one step at each working stroke of

the adding machine. At each working stroke the type arms 217 are pressed against the control strip, which thus receives prints from the type arms. The latter carry figures arranged in a row one above the other and with such intervals that only one figure at a time will assume printing position relative to the control strip. The connection between the toothed segments 213 and the type arms 217 is such that a turning of the toothed segments from their initial positions will cause the type arms to move upwards. Thus, the angle positions of the toothed segments 213 will determine what figures are printed on the control strip by the various type arms 217, it being so arranged that the amount printed on the control strip is the same as that entered into the totalizer of the adding machine.

For every ticket issued by the machine the control strip should be provided with an indication of the clerk who operated the machine at the occasion in question. For this purpose one of the arms 217 carries types for printing marks identifying the various clerks in charge of the machine. The printing position of said arm is determined by a link 220 which is of somewhat different construction than the links 217. The construction and operation of this special link 220, which is seen in Fig. 33, will be clearly described in the paragraph dealing with the clerks' lock.

The feed roller 218 for the control strip belongs to the standard equipment of the adding machine used by us as counter. The control strip is formed to a roll 221 mounted in the machine frame 1 beneath the counter, from where it is led upwards outside the counter as well as the machine frame 1. On its way up to the feed roller 218 the control strip passes inside a projection formed from a lever rockably mounted in the machine frame 1, which lever is adapted to cooperate with elements for preventing a depression of the start key when the control strip is almost used up. This arrangement, however, will be described more in detail in a special paragraph referring to the various means for preventing unwanted operations of the machine. From the feed roller 218 the control strip passes on to a roller 222 mounted in the machine frame 1 where it is wound up.

The drive shaft of the counter is indicated by reference character 223. It should be mentioned that the adding machine which we prefer to use as counter is of the common type wherein the drive shaft during a working stroke of the machine is rotated through a quarter of a full revolution and back again. The necessary rotation of this shaft is imparted to the same by a toothed rack 224, at its lower end connected with a two-armed lever 225. Said lever is mounted on a shaft 226 journalled in the machine frame 1. At its free end the lever 225 carries a roller 227 which is urged by a spring 228 extending between the lever 225 and the bottom plate of the machine frame 1 to engage on a cam 229 fast on the main shaft 2, said cam being indicated in dashed lines in Fig. 1. The cam 229 is of such shape that the rotation of the main shaft 2 will cause the toothed rack 224 to rotate the shaft 223 a quarter of a full revolution and back again.

For printing consecutive numbers corresponding to those of the printed tickets on the control strip the following means are provided, see Fig. 33. In a vertical frame wall of the counter there is pivoted a two-armed lever 230, the lower end of which is curved as shown on the draw-

ing. Pivotedly connected with the upper end of the lever 230 is an arm 231 which carries a consecutive counter mechanism 232 of a well known type. The type wheels belonging to this consecutive number counter are mounted in a frame 233 fixed to the arm 231, said frame 233 resting on flanges 234 projecting from a frame construction 235. The frame 235 encloses and serves as a guide for the frame 233 of the consecutive number counter 232. The type wheels of the consecutive number counter are so positioned relatively to the feed roller 218 for the control strip that a slight displacement of the type wheels to the right will cause the same to print the actual consecutive number on the control strip. The consecutive number counter 232 forms no part of this invention and it will suffice to state that the restoration of the type wheels from printing position to the initial position shown in Fig. 33 will cause an advancement of one unit. It will also be understood that the consecutive number counter 232 must be actuated at each working stroke. When the drive shaft 223 of the counter is caused by the toothed rack 224 to rotate in the manner described above another shaft 236, which is also a standard element of the adding machine used by us as counter, is caused to rotate in the same manner, i. e. it is rotated anti-clockwise through a quarter of a full revolution and then back again to the initial position. Fast on the shaft 236 is a one-armed lever 237 at its end carrying a roller 238. This roller is adapted to engage with the curved lower arm of the two-armed lever 230. A spring 239 constantly strives to hold the lever 230 in the position shown in Fig. 33. However, when the counter performs a working stroke the roller 238 on the lever 237 moves into contact with the lever 239 and rocks the same in such manner that its upper arm will push the arm 231 carrying the consecutive number counter 232 towards the control strip, the actual consecutive number being thereby printed on the control strip. Towards the end of the working stroke the lever 237 is rocked back into its initial position, the spring 239 restoring the lever 230 and the elements connected therewith to initial positions. When the consecutive number counter 232 moves back into the frame 235 a projection 240 on the inner wall of the same actuates the consecutive number counter mechanism to advance one unit.

Means for reading off and zeroizing the counter

In all adding machines there are two special keys, one to be depressed when the accumulator of the machine is to be read off, while the other should be depressed before a zeroizing of the accumulator can take place. The shafts of these two keys of the adding machine used by us as a counter are shown in Fig. 35 in dot and dash lines and indicated by reference characters 241 and 242, respectively. Since the counter in itself does not form part of our invention it will suffice to say that an actuation of the shaft 241 is necessary for reading off the counter and that a depression of the shaft 242 is likewise needed for zeroizing the accumulator of the counter.

For carrying through a reading off or zeroizing operation there is used a specific arm 243 mounted in one of the magazines and substantially having the same shape as the printing arms 16, see Fig. 34. At its free end the arm 243 carries a projection 244 which is adapted to co-operate with the means hereinafter described.

Said means are partly indicated in Fig. 3 and 75

shown on a larger scale in Figs. 35-39. Fixed to a vertical wall of the machine frame is a stationary U-shaped member 245 in which a plate 246 is pivotally mounted, said plate 246 being under the control of a draw spring 247. The plate 246 is pivoted on two pins 248 extending inwardly between the legs of the U-shaped member 245. Each pin 248 is formed with a groove 249 for guiding the printing arms 16 as well as the specific arm 243 when being moved into operative position. The rockable plate 246 carries a transverse member 250 formed with an upstanding flange 251, said flange being intended at a certain position of the plate 246 to engage in recesses 252 of the arms 214 previously mentioned. Mounted pivotally on the transverse member 250 is an arm 253 carrying two projections located on either side of the turning shaft 254 of said arm. One of said projections, indicated by reference character 255, is adapted to co-operate with the projection 244 of the arm 243, previously mentioned. The other projection of the arm 253, indicated by 256, is adapted to co-operate with a pin 257 carried by the stationary member 245. The arm 253 is under control of a draw spring 258, one end of which is fixed to the projection 255 while its other end is attached to a pin on the rockable member 246.

On its underside the plate 246 carries a member 259. A pin 260 fast on the member 259 engages in a slot 261 formed in the plate 246, the member 259 being thus displaceable and turnable relatively to the plate 246. By the action of a thread spring 262 fixed to the plate 246 the member 259 strives to assume certain positions relatively to the member 246 which will be explained later. The member 259 is also formed with a downwardly extending projection 263 which is adapted to cooperate with the projection 244 of the arm 243 or with the printing arms 16. Also extending downwardly from the member 259 is another projection 264, said projection and a projection 265 also formed from the member 259 at certain positions of said member being adapted to co-operate with the locking pin 105.

The rockable plate 246 is formed with an extension 266 to which by means of a pin and slot connection is slidably attached a member 267, said member carrying a sidewardly projecting pin 268. The latter is adapted to be actuated by a rockable arm, which is in operative connection with a lock which will be described in detail later. The member 267 carries two downwardly extending pins 269, 270 said pins at the displacement of the member 267 being adapted to co-operate, one at a time, with the members 241 and 242 of the counter.

The member 246 is also formed with an oblique surface 271 adapted at certain occasions to co-operate with the member 259. The fixed U-shaped member 245 also carries a stop roller 272 said stop preventing the arms 16 and the arm 243 from being rocked past their operative positions.

Start mechanism

The start mechanism, see Figs. 40 and 41, comprises a start key 273 fast on bar 274 which is slidably mounted in the machine frame 1, two pins 275 and 276 fast on the frame 1 engaging two slots 277 and 278 cut in the bar. A spring 279 interposed between a pin 280 fast on the bar 274 and the pin 276 on the machine frame normally holds the bar 274 in its upper position. To the lower end of the bar 274 there is pivoted

a pawl 281 which is intended to engage with a recess 282 cut in the edge of a cam 283 mounted on the drive shaft 3. As previously mentioned the shaft 3 is connected by means of a coupling to an electric motor 4, by which the drive shaft 3 is rotated during the working stroke of the machine. The rotation of the drive shaft 3 is transmitted to the main shaft 2 by means of a coupling to be described later.

The bar 274 also carries a transverse member 284 adapted to cooperate with two leaf springs 285. Said leaf springs 285 and two other similar springs 286 serve as a contact for closing the electric current to the electric motor 4.

It is obvious that a depression of the start key 273 will cause the pawl 281 to disengage from the cam 283 and the transverse member 284 to actuate the electric contact above described.

Coupling for connecting drive shaft and main shaft

As has been mentioned above the machine is driven by an electric motor which is connected by means of a coupling to the drive shaft 3. The motor and the coupling, however, can be of any suitable construction and do not form part of this invention. For transferring the rotation of the drive shaft 3 to the main shaft 2 the coupling hereinafter described is provided, see Figs. 42-44.

A gear 287, which is loosely mounted on the drive shaft 3, is rigidly connected by means of a hub portion 288 with the cam 283 previously mentioned, the gear and the cam being situated on either side of a vertical wall of the machine frame 1. As will be seen from Fig. 42 the cam 283 is provided with a recess 282 which is engaged by the pawl 281 as long as the machine is at rest. From the said recess and in an anti-clockwise direction, see Fig. 42, the diameter of the cam 283 diminishes, which is of essential importance for the operation of the coupling. Pivoted on the cam 283 is a two-armed lever 289 of angular shape, one end of which is adapted to cooperate with the pawl 281. To the other end of the lever 289 is fixed one end of a spring 290, the other end of which is fixed to the cam 283. Said spring strives to rock the lever 289 in a direction which will be clear from Fig. 42. As long as the pawl 281 engages the recess 282 of the cam 283 such rocking, however, is prevented. Fast on the drive shaft 3 is a hub 291, in the surface of which a number of recesses 292 are cut, see Figs. 42 and 44. These recesses are intended to cooperate with a projection 293 extending downwardly from the lever 289. It is obvious that an engagement between the projection 293 and one of the recesses 292 will rigidly connect the drive shaft 3 and the gear 287. The latter is constantly in mesh with a gear 294 of the same size fast on the main shaft 2.

The coupling now described operates in the following manner. When the start key 273 is impressed the pawl 281 is raised from its engagement with the recess 282 in the cam 283. At the same time the contact 285-286 for closing the electric current to the motor is actuated as above described and the drive shaft 3 starts rotating. The lever 289 is now also released from its engagement with the pawl 281 and, consequently, when one of the recesses 292 in the hub 291 fast on the drive shaft 3 arrives beneath the projection 293 on the lever 289, the spring 290 causes said projection to enter the said recess 292. The cam 283 and the gear 287 are now rigidly connected

with the drive shaft 3 and, consequently, participate in its rotation. If the start key 273 is still actuated the pawl 281 will be retained in its uplifted position and the machine will perform one working stroke after the other. As soon as the actuation of the start key 273 ceases, however, the pawl 281 falls down on the edge of the cam 283 and glides along the same until it arrives at the recess 282. Now the pawl 281, owing to the diminishing diameter of the cam 283, strikes against the lever 289 and lifts the projection 293 of the same against the action of the spring 290 out of engagement with the recess 292 of the hub, the cam 283 and the hub 291 on the drive shaft 3 being thus disconnected again. From the above it will be clear that the cam 283 and the gear 287 rigid therewith will always stop rotating in exactly the same position after having performed one, two or more full revolutions. Since the gear 294 fast on the main shaft 2 and meshing with the gear 287 is of the same size as the latter the main shaft will also always stop in the same position after having performed one, two or more full revolutions.

To enable an operation of the machine by hand, should there occur any breakage in the electric current in which case the drive shaft 3 and the main shaft 2 must be disconnected from each other, it has been arranged as follows, see Figs. 42-44. On a shaft 295 there is slidably mounted a U-shaped member 296, one leg of which is bent somewhat inwards and formed with two side flanges 297. On the portion connecting the two legs of the member 296 there is fixed a lug 298, a spring 299 mounted around a rod 300 and compressed between the lug and the machine frame 1 striving to force the U-shaped member 296 outwards from the machine frame 1. Pivoted connected with the said U-shaped member 296 is another U-shaped member 301, the free ends of which are turnably mounted in a groove in a stationary rail 302, as seen from Figs. 42 and 43. The legs of the U-shaped member 301 embrace a sleeve 303 which is slidably mounted on the hub 291 fast on the drive shaft 3. Two pins 304 fast on the sleeve 303 project through apertures 305 provided one in each leg of the U-shaped member 301. The inward edge of the sleeve 303 is of conical shape and is adapted to cooperate with a small roller 306 mounted on the lever 289. The elements now described operate in the following manner. It is supposed that the machine is performing a working stroke when the electric current is suddenly broken. The drive shaft 3 is then still connected with the main shaft 2 in the manner previously described. To finish the working stroke thus begun and for the continued operation of the machine a crank lever 307 is now pushed on to the shaft 295. A pin 308 on said shaft is brought to engage a slot 309 in the crank lever 307, said pin and slot thus determining how far the crank lever 307 can be pushed on to the shaft 295. The crank lever 307 strikes against one leg of the U-shaped member 296 which is thus urged against the action of the spring 299 inwards. This displacement of the U-shaped member 296 will cause the U-shaped member 301 connected therewith to rock inwards, the sleeve 303 being thereby moved inwards on the hub 291. At such displacement of the sleeve 303 the conical edge of the same enters beneath the roller 306 carried by the lever 289 and raises the same out of its engagement with one of the recesses 292 in the hub 291. By applying the crank lever 307 the drive shaft 3 is thus disconnected.

nected from the main shaft 2. A rotation of the shaft 295 by turning the crank lever will be transferred to the main shaft 2 by a gear 310 fast on the shaft 295, which gear meshes with a gear 311 in its turn in mesh with the gear 287. The gears 310 and 311 are of such size that the shaft will have to make two complete revolutions to cause the main shaft 2 to make one full revolution.

Locking means for preventing unwanted operation of the machine. Ticket strip casing

It is of importance that it shall not be possible to start the machine if some elements of the same are not correctly adjusted. It should also be provided for that the machine cannot be operated if the ticket strip or the control strip are at an end. Moreover, only those who are in charge of the machine shall be able to operate the same. To meet these requirements the following means are provided, see Figs. 40 and 41.

Near its upper end the bar 274 of the start key 273 is formed with two lateral projections 312 and 313. The projection 312 is adapted to cooperate with a two-armed lever 314 pivoted on a pin 315 fast on a horizontal portion of the frame 1. The said lever 314 is connected with the clerks' lock which will be described in a following paragraph. The projection 313 carries a sidewardly extending pin 316, which at the depression of the start key normally goes clear of an angular projection 317 fast at one end of a bar 318. The projection 317 as well as another angular projection 319 fast on the bar 318 are slideable on a cross rod 320 mounted in the machine frame 1, see Figs. 5 and 6. A spring 321 compressed between the projection 319 and a disc 322 fast on the cross rod 320 strives to hold the projection 317 out of the path of movement of the pin 316. At its other end the bar 318 is bent at right angle to form a projection 323 which is urged by the spring 321 to engage with the disc 76 of the magazine adjusting device. When the hand wheel 59 is operated the disc 76, as will be recalled from the previous description, is moved out of engagement with the pin 83. This movement also imparts a movement to the bar 318 with the projection 317 thereon against the action of the spring 321. As long as the hand wheel is actuated the projection 317 will be situated right beneath the pin 316 on the start key bar 274 and thus prevent a depression of the start key. Should the operator loosen his grip on the hand wheel without having adjusted the magazines correctly the disc 76 will not return to its initial position, a depression of the start key being thus still prevented by the projection 317.

As can be seen from the drawing the bar 274 near its upper end is bent in such a manner that the upper part and the lower part of the bar still extend in the same direction but in different planes parallel to each other. Quite near the projections 312 and 313 the bar 274 is formed with another rearwardly extending projection 324, which in its turn is formed with an angular projection 325. The latter is adapted to cooperate with an arch-shaped stop member 326 fast on one leg of the U-shaped lever 26. As will be recalled selection of magazine is effected by adjusting the lever 26 which serves to impart the required movements to the elements constituting the magazine selecting device. The projection 326 is so adjusted that it is out of the path of movement of the projection 325 when the lever 26 assumes one of its two end positions, i. e. when

one or the other of the magazines is selected. In all other intermediary positions of the lever 26 the stop member 326 thereon will prevent a depression of the start key by standing in the way of the projection 325 of the start key bar 274.

For preventing an operation of the machine when the control strip is at an end the bar 274 is provided with still another projection 327 adapted to cooperate with a projection 328 formed at one end of a slide 329. Said slide is carried by the machine frame 1, two pins 330 and 331 fast on the frame 1 projecting through two slots 332 and 333 cut in the slide. Near its other end the slide 329 is formed with a recess 334 adapted to cooperate with a projection 335 of angular shape fast on a lever 336 which is pivoted on a pin 337 fast on the machine frame 1. A spring 338 extending between a lug 339, formed from that part of the machine frame 1 which is situated beneath the slide 329, and the lever 336 normally tries to rock the lever to the left, see Fig. 41. However, such rocking movement is prevented by the control strip 219 which, as previously mentioned, is passed outside and against the machine frame 1 but inside an angular projection 340 formed from the lever 336. In other words, the control strip is squeezed with a light pressure between the machine frame 1 and the projection 340. When the control strip is almost used up the end of the same slides out of engagement with the projection 340, the lever 336 being then rocked to the left by the spring 338. The rocking movement imparted to the lever 336 causes a displacement of the slide 329, the projection 328 of which enters into the path of movement of the projection 327 fast on the bar 274. Thus, the start key 273 cannot be depressed unless a control strip is inserted in the counter.

For preventing a depression of the start key when the ticket strip 24 is almost used up the following means are provided, see Figs. 2, 45, 46. As seen from the drawings the ticket strip roll 341 is mounted in a casing 342 at the top of the machine. From this roll the ticket strip passes through an opening 343 in the casing to enter into a flattened funnel 344. In said funnel there is provided two apertures 345 and 346, the first mentioned of which is engaged by a small rounded plate 347 fast on a lever 348 of angular shape. The latter is pivoted on a pin 349 fast on the machine frame 1 and a spring 350 interposed between the middle portion of the lever 348 and the downwardly extending shaft of the funnel 344 urges the plate 347 to enter the aperture 345. As long as there is anything left of the ticket strip in the funnel 344 the same prevents the plate 347 from advancing further through the aperture 345 but when the ticket strip is used up and the end portion of the same has left the funnel 344 the spring 350 causes the lever 348 to lock, the plate 347 being thereby advanced through the funnel 344 and as far as is permitted by the aperture 346 which is not large enough to let the plate 347 quite through. This movement of the lever 348 actuates a Bowden cable 351, one end of which is fixed to the lever 348. The other end of the said Bowden cable is fixed to a pawl 352, see Figs. 42 and 43. The latter is pivoted on a pin 353 fast on the frame construction 1 which carries the coupling for connecting the drive shaft 3 and the main shaft 2. The pawl 352 is adapted to cooperate with the lever 289 but is normally held out of engagement with the same. However, when the ticket strip is at an end and the last portion of the same leaves the

funnel 344 the lever 348 is rocked by the spring 350 as previously described and the Bowden cable 351 tensioned. This tensioning of the Bowden cable causes the pawl 352 to engage with the lever 289. If the start key is now depressed and the pawl 281 connected therewith is rocked out of engagement with the recess 282 of the cam 283 as well as with the lever 289, the cam 283 is still locked by the pawl 352 engaging with the lever 289. The drive shaft 3 will then be free to 10 rotate as long as the electric current is closed by the depressed start key, there being no engagement between the projection 293 of the lever 289 and the recesses 292 of the hub 291 fast on the drive shaft. When a new ticket strip roll is 15 again inserted in the casing 342 and in the funnel 344 the lever 348 is rocked back into its original position against the action of the spring 350, the pawl 352 disengaging the lever 289. The machine is now ready for operation again.

From Figs. 45 and 46 it will also be seen that the ticket strip roll 341 is mounted on a drum 354 which is loose on a shaft 355. The drum 354 is formed by bending two plates 356 and 357 of a thin springy metal material to a substantially 25 semi-circular shape and fastening the same together, see Fig. 46. As will be seen from this figure the contacting surfaces of the two halves are also bent to form an opening for the shaft 355. The plates 356 and 357 are further bent in such 30 manner that the drum formed by the same is somewhat compressible. When a ticket strip roll is to be applied, the drum 354 is thus compressed until it can be inserted in the central opening of the roll. When released the two halves of the drum 354 will strive to assume normal position, the ticket strip roll being then held in a firm grip on the drum. This construction of the drum 354 also makes it possible to use ticket strip rolls with 35 central openings of varying sizes. The shaft 355 is journaled at one end in a bar 358 suspended in and extending downwardly from the lid 359 of the casing. The bar 358 is turnable around a rod 360 mounted in two plates 361 and 362 fixed to the lid 359. The lower edge of the plate 361 is cut to 40 form a flap 363 which is bent somewhat inwards so that the free end of the same is in alinement with the edge of the bar 358. Consequently, when the lid 359, which is hinged to the top of the machine at 364, is raised, the bar 358 with the ticket strip roll hanging thereon is lifted vertically until the flap 363 strikes against the edge of the bar, 45 see Fig. 46. At continued raising of the lid 359 the bar 357 will be swung out of the casing, the drum 354 being thereby more easily accessible from outside.

Clerks' lock

The clerks' lock and the elements for locking the start key against depression when the clerks' lock is not actuated by a key are shown in Figs. 47, 48 and 50. The clerks' lock is indicated by reference character 365 and is mounted at the top of the machine in a frame construction.

As can be seen from the drawings the clerks' lock is of the well known Yale-type. To the back of the cylinder 366 there is attached a cam 367 which is adapted to be turned by a key inserted in the lock. On a vertical portion of the frame 1 there is pivotally mounted a one-armed lever 368 which is bent in a way clearly shown in Fig. 50. The lever 368 is formed with a lateral projection 369 which is bent at right angles at its end to form another projection 370. The latter is provided with an aperture to permit a shaft 371 to

project through the same. The shaft 371 is slidably mounted in two vertical portions of the frame 1, a spring 372 compressed between one of said frame portions and a roller 373 fast on the shaft 371 constantly urging the latter to the left, see Fig. 47. To the opposite end of the shaft 371 there is fixed another roller 374 which is held by the spring 372 in contact with the projection 370 on the lever 368. Another projection 375 at the upper end of the lever 368 engages on the cam 367 attached to the cylinder 366 of the clerks' lock. In the edge of the cam 367 there is cut a recess 376, which is adapted to cooperate with the upper projection 375 of the lever 368. When there is no key inserted in the clerks' lock the projection 375 is out of engagement with the recess 376 in the cam 367. When a key is inserted in the clerks' lock and turned to the right, see Figs. 47 and 48, the cam 367 is so turned that the projection 375 on the lever 368 can enter into the recess 376. Since the lever 368 can now be rocked somewhat to the left, see Figs. 47 and 48, the spring 372 will cause the shaft 371 to slide correspondingly to the left. At such movement of the shaft 371 a third roller 377 fast thereon will move out of engagement with one end of the two-armed lever 314 previously mentioned. As will be recalled the other end of said lever 314 is adapted to cooperate with the projection 312 on the start key bar 274. A spring 378 extending between one end of the lever 314 and a stud 379 on the frame 1 strives to hold the lever 314 at such distance from the shaft 371 that the roller 377 can pass over the end of the lever 314. It is obvious that as long as the roller 377 engages the two-armed lever 314 the same cannot be rocked by a depression of the start key 273. Thus, not until a clerks' key has been inserted in the lock 365 and the cam 367 has been turned so as to allow the projection 375 on the lever 368 to enter the recess 376 in the said cam is a depression of the start key possible. When the inserted clerks' key is turned back again the projection 375 is forced out of engagement with the recess 376 in the cam 367 and the lever 368 is rocked to the right, thereby with its projection 370 causing the shaft 371 to slide to the right against the action of the spring 372. At such sliding movement of the shaft 371 the roller 377 thereon will move back into engagement with the left end of the lever 314 which again locks the start key against depression.

The clerks' lock, however, is not only intended for locking the start key against depression. By means to be described hereinafter it is also in operative connection with that setting member in the counter which adjusts the arm 217 carrying types for printing on the control strip indications of the operating clerk in charge of the machine. Pivoted to a pin 380 fixed to a vertical portion of the frame 1 is a two-armed lever 381 of angular shape, the arms of the same being connected with each other by a transverse portion 382. The upper arm of the two-armed lever 381 is at its free end formed with an angular projection 383 which is situated right behind the key hole of the clerks' lock. At its free end the other arm of the two-armed lever 381 carries a downwardly extending rod 384. At its other end the rod 384 is connected with one end of a two-armed lever 385 pivoted on a pin 386 fast to the frame of the counter, see Fig. 33. The opposite end of the two-armed lever 385 engages with a pin 387 fast on a projection 388 formed from a plate 389. Said plate is provided with two slots 390 and 391 which are en-

gaged by two pins 392 and 393 fast on the frame of the counter, the plate 389 being thus slidable relatively to the counter frame. A spring 394 fixed at one end to the projection 388 on the plate 389 and at the other end to a pin 395 fast to the counter frame is constantly trying to raise the plate 389 upwards. The action of the spring 395 is also transmitted to the two-armed lever 385 by means of the pin 387, the spring 394 thus also serving to lower the rod 384, i. e. to force the plate 383 towards the cylinder 366 of the clerks' lock. However, the keys intended for operation of the clerks' lock are of such length that, when inserted in the lock, they project all through the key hole, the end of the key thus striking against the plate 383 on the upper arm of the two-armed lever 381. It is obvious that the insertion of a key in the clerks' lock will cause the two-armed lever 381 to rock, the rod 384 being thereby raised and the two-armed lever 385 pivoted to the counter frame being rocked correspondingly. Such rocking movement of the lever 385 will cause the plate 389 to move downwardly against the action of the spring 391. At its upper end the plate 389 is cut in a stepwise manner. As can be seen from Fig. 33 a projection 396 formed from one, 220, of the setting members of the counter is adapted to cooperate with the said steps at the upper end of the plate 389. As has been mentioned above all setting members of the counter are longitudinally displaced at the working stroke of the counter. Consequently, the position of the plate 389 will decide the length of the movement imparted to the above mentioned setting member 220 during the working stroke of the counter. This setting member in its turn determines the printing position of that type carrying arm 217 which is indented for printing indications of the clerk operating the machine. From the construction described above it will now be understood that all clerks in charge of the machine can have keys of identical shape which fit in the same lock, a varying of the length of the keys being sufficient to obtain different indications on the control strip 219.

Lock for effecting zeroizing of the counter

In a following paragraph it will be described how the counter is read off and zeroized. From the paragraph, wherein the counter is described, it will be recalled that the slidable member 267 carries two downwardly extending pins 269 and 270 which are adapted to actuate, one at a time, those setting members 241 and 242 of the counter, the depression of which is necessary for effecting a reading off or zeroizing of the counter. For adjusting the slidable member 267 there is provided in the same frame construction as carries the clerks' lock a similar lock 397. To the back of the cylinder 398 of said lock there is eccentrically fixed a plate 399 carrying a pin (not visible in the drawing). Turnable around said pin is the upper end of a downwardly extending link 401, the other end of which is turnably connected with one arm of a two-armed lever 402. The latter is pivoted to a shaft 403 fixed to a vertical portion of the machine frame 1. The free end of the lower arm of the lever 402 is provided with a recess 404 which is adapted to engage with the pin 268 fast on the slidable member 267. It will be understood that a turning of the cylinder 398 of the lock 397 in clockwise direction from the position shown in Figs. 47-49 will impart a rocking motion to the lever 402, the lower arm of which will displace the

75

slidable member 267 correspondingly. It should also be mentioned that when there is no key inserted in the lock 397 the slidable member 267 assumes such position that the pin 269 on the slidable member 267 is situated right above the setting member 241 of the counter, the depression of which is necessary for effecting a reading off of the counter. When a key is inserted in the lock 397 and turned in clockwise direction, see Figs. 47 and 48, the slidable member 267 is displaced by the lever 402 in such manner that the pin 270 will be situated right above the setting member 242 of the counter, the depression of which is necessary for effecting a zeroizing of the counter.

As seen from Fig. 47 the link 401 is formed with a sidewardly extending projection 405 which is adapted to cooperate with a roller 406 fast on the shaft 371. When the cylinder of the lock 397 is turned in one direction or the other the excentrical mounting of the link 401 will cause the same and the projection 405 thereon to perform not only a vertical movement but also a short reciprocating movement to the right and then back to the left. Such movement of the projection 405 will cause the shaft 371 to slide correspondingly first to the right against the action of the spring 372 and then back to the left. When the shaft 371 is displaced to the right, i. e. when the cylinder of the lock 397 assumes an intermediary position, the roller 371 on the shaft 371 assumes a position right above the lever 314, a depression of the start key being thereby made impossible. From the above it will thus be clear that the machine cannot be started, unless the lock 397 is correctly adjusted.

Mode of operation

Although it is believed that the above description will suffice for a complete understanding of the machine according to our invention a resume of its operation will be given herein-after.

By means of the selecting mechanism that magazine which contains the printing arm 16 corresponding to the ticket to be printed is first selected. The magazines are then so adjusted that the said arm 16 will assume its "ready position" right in front of its operative position. This is effected by turning the hand wheel 59, the indicator drums 60 fast on the same shaft 27 as the hand wheel also being turned thereby. When the indicator drums 60 have been adjusted into such position that the name of the desired station is visible through the corresponding opening in the machine casing that arm 16 which corresponds to the said station assumes its "ready position" in front of its operative position.

After the magazine selecting and adjusting mechanisms have been correctly adjusted, and after a key has been inserted in the clerks' lock, the start key can be depressed and the working stroke of the machine effected.

Upon depression of the start key 273 the electric current for the motor 4 is closed and the working stroke begins that is the turning of the main shaft 2 through a full revolution. The rotation of the main shaft begins as soon as the necessary connection between the same and the drive shaft 3 has been established as described above. First, the mechanism for fixing the magazines in their respective positions is first put into function i. e. the flange body 92 is brought to engage the flanges 94 provided on the back wall of one of the magazines. A rock-

ing movement is then imparted to the arms 39, that slide 45 which is now connected with one of the arms 39 through the pin 38 mounted in the said arm thereby being displaced. Since the projection 50 of said slide member 45 engages in the recess 19 of that printing arm 16 of the selected magazine which assumes "ready position," said arm at the displacement of the slide member is rocked into its printing position, see Fig. 3. At the same time the consecutive number counter and the date printing mechanism are moved into printing position. When being brought into operative positions the arm 16 and said mechanisms pass over and against the colour rollers 149 and 150, respectively, the printing means being thereby supplied with printing colour. As the arm 16 reaches its operative position the pin 161 snaps into the recess 22 of the arm 16, thus preventing the same from rebounding.

This effected, the movable pressure table 98 receives an upward movement, at the beginning of which the locking pin 105 on said pressure table enters into the opening 23 in the arm 16, thus locking the same in its operative position. At the continued movement of the pressure table 98 the ticket strip 24 advanced above said table is pressed upwards against the abovementioned mechanisms as well as against the printing plate of the arm 16, the ticket strip thus receiving the desired prints. The upward movement of the pressure table 98 will also cause an advancement of the step wheel 185 connected with the colour feeding service. At such advancing of the step wheel the shaft 181 of the colour container may be caused to make half a revolution as above described, thereby causing a supply of colour to the colour roller system. At the same time the counter performs its working stroke, the cam 229 co-operating with the roller 227 on the lever 225 imparting a rocking movement to said lever. By the rocking movement of lever 225 the toothed rack 224 connected therewith is first moved upwardly and then downwardly, the gear fast on the shaft 223 and in driving mesh with the toothed rack 224 imparting a reciprocating rotative movement to the shaft 223 of the counter.

At the working stroke of the counter the levers 214 connected with the link members 212 of the counter are first brought to enter into engagement with the recessed edge of the plate 21 attached to the arm 16 assuming operative position. The control strip 217 is then provided with a print, an accumulation of the amount determined by the recessed edge of the plate 21 taking place at the same time. On the control strip, by means of devices previously described, there is also recorded the clerk who is operating the machine and the number of the printing plate having been used, signs for indicating special kinds of tickets, number of machine and consecutive ticket numbers. After the printing the control strip is fed forward in usual manner. As long as the counting and printing operation is going on in the counter the pressure table 98 assumes such position that the locking pin thereon locks the arm 16 in its operative position.

The various elements now return to their inoperative positions, i. e. the locking pin 105 is caused to disengage the aperture 23 and the pin 161 is moved out of engagement with the recess 22 of the arm 16, said arm being returned to its inoperative position. The consecutive number counter and the date printing mechanism are also restored into initial position. During the

last period of the working stroke of the machine the ticket strip 24 is advanced and the printed portion of the same is cut off by means of the cutting mechanism. The printed ticket is delivered through the funnel 211 opening in the casing of the machine. Finally, the flange body 92 is returned to inoperative position.

Reading off and zeroizing of the counter

10 The means for reading off and zeroizing the accumulator of the counter operate as follows:

As above described the machine also comprises a lock 397 of such construction that upon turning of a key inserted into the same the lever 402 through co-operation with the pin 268 on the 15 slideable member 267 causes said member to slide in one direction or the other.

For reading off the accumulator of the counter the member 267 is brought into the position

20 shown in Figs. 35 and 36, the pin 269 being then situated right above that impulse member 241 of the counter, the depression of which is necessary to enable such reading off. The reading off and zeroizing means above described then assume the positions shown in Figs. 35-37. After a selection of the corresponding magazine the hand wheel 59 is turned to bring the arm 243 in its "ready position." After depression of the 25 start key 273 the arm 243 is moved into its operative position in the same way and by means of the same elements as the arms 16. The projection 244 of the arm 243 then first contacts the downwardly extending projection 263 of the member 259 and imparts to said member a rocking movement. The projection 244 then contacts the projection 255 on the rockable arm 253, the latter being thereby also rocked. The projection 256 on the arm 253 is hereby moved out of its engagement with the pin 257 on the stationary U-shaped member 245. The rockable plate 246 through the action of the draw spring 247 is now rocked upwardly to some extent, the flange 251 on the transverse member 250 thereby engaging the hook-shaped end portions of the arms 214, the latter being thereby held locked. After the arm 243 has been moved into contact with the stop roller 272 the projection 263 on the member 259 through the action of the spring 261 has snapped in behind the projection 244 of the arm 243. The elements now assume the positions shown in Figs. 38 and 39.

The continued working stroke of the machine is quite the same as described before. However, the ticket now printed by the printing plate carried by the arm 243 is not provided with the same prints or the same text as a ticket intended for sale but with such indications as are of interest in connection with the operation now going on.

When the arm 243 is returned to the magazine 60 the member 259 is displaced to the left through co-operation of the projection 244 with the projection 263. Owing to the turning movement performed by the arm 243 and owing to the position of its turning point relative to the member 259 the projection 244 will slip out of its engagement with the projection 263 after the member 259 has reached such position that the downwardly extending projection 264 on the member 259 assumes a position right above the locking pin 105. At this movement the member 259 co-operates with the oblique surface 271 for the purpose of adjusting said member in the correct position. The working stroke thus performed is necessary in order to allow such tens transmitting operations to take place as may have be-

come due after the foregoing working stroke of the counter.

After this working stroke of the machine the start key 273 is again depressed, the arm 243 being again moved into its operative position.

This time the projection 244 on the arm 243 passes the projection 263 without contacting with the same, the member 259 now being inactive relative to the projection 244. Nor does the arm 243 actuate any other members when being moved into its operative position. The locking pin 105 on the movable pressure table, however, when being moved upwardly strikes against the projection 264, the plate 246 being then rocked in such manner that the pin 269 on the member 267 actuates the member 241 of the counter, i. e. that member which effects the totalizing for reading off the accumulator. On the control strip that sum is now printed which, at the moment, is accumulated. During the rocking movement of plate 246 the projection 255 glides along the front portion of the projection 244, the arm 253 at the movement of plate 246, consequently, still assuming that position which it received when the arm 243 was turned into its operative position for the first time.

At the downward movement of the locking pin 105 the plate 246 through the action of the spring 247 resumes its position described above, see Fig. 39. The member 259 remains in its position also at the returning of the arm 243 to the magazine. The rockable plate 246, thus, is still held in its upper position by means of the draw spring 247.

When the machine is again to be used for printing a ticket the selected arm 16, the free end of which is somewhat broader than the arm 243, will contact with the projection 263 on the member 259, the latter through the action of the spring 262 being then urged to assume its initial position as shown in Fig. 36, the projection 265 on the member 259 being now situated right above the locking pin 105. When moving upwardly the locking pin 105 strikes against the projection 265, the plate 246 resuming its horizontal position and being held there by the projection 256 resuming its engagement with the fixed pin 257, the arm 253 being turned back into its initial position by the draw spring 253.

A zeroing of the accumulator of the counter is effected in the same manner as the above described reading off operation. The only difference is that the lock 397 controlling the reading off and zeroizing means is so adjusted that the member 267 assumes a position in which the pin 270 is situated right above that impulse member 242 of the counter, the depression of which is necessary for zeroizing the accumulator.

A simplified embodiment

At a station where there is no need for more tickets than can be printed by the arms 16 contained in one magazine there may be used a machine provided with only one magazine. Such simplified embodiment of the machine is shown in Fig. 51. According to this embodiment the whole magazine selecting mechanism can be dispensed with, i. e. the lever 26, the link 28, the slide 29, the displaceable shaft 35 with its pin 34, one of the arms 39 with the pin 38 associated therewith, and one of the slide members 45. The magazine frame, however, may preferably remain, although without any arms 16 in it, said arms being replaced by a counterweight 408 for the purpose of obtaining the counterbalancing as described above.

Finally, it should be stated that we do not de-

sire to limit our invention to the embodiments herein disclosed, for it may be varied in many ways within the claims to follow.

Having now described our invention, what we claim as new and desire to secure by Letters Patent is:

1. In a ticket printing machine having a frame, two vertically adjustable magazines each comprising a plurality of movable arm members, each of said arm members having a ticket printing plate fixed thereto, locking means for securing said magazines in different vertical positions, means for selectively moving one arm member from either of said magazines at each locked position from a storage position inside the magazine to an operative position outside the magazine, and means for moving the magazines into said different positions comprising an adjusting wheel fixed to a horizontal shaft mounted in the machine frame, said shaft having fixed thereto two indicator drums corresponding to the printing arms of the magazines and indicating which of the arms, that, at the moment, assumes a position right in front of its operative position, 25 said shaft having also fixed thereto a toothed wheel meshing with another toothed wheel fast on one end of a shaft mounted in the machine frame perpendicularly to the firstmentioned shaft, the lastmentioned shaft at its other end carrying another toothed wheel meshing with two toothed racks located opposite one another and each being fixed to one of the magazines, the connection between the adjusting wheel and its shaft being rigid enough to ensure a distinct adjustment of the magazines but at the same time loose enough to allow a continued turning of the wheel after the magazines have reached their end positions.

2. In a ticket printing machine having a frame, 40 two vertically adjustable magazines each comprising a plurality of movable arm members, each of said arm members having a ticket printing plate fixed thereto, locking means for securing said magazines in different vertical positions, 45 means for selectively moving one arm member from either of said magazines at each locked position from a storage position inside the magazine to an operative position outside the magazine, and means for moving the magazines into 50 said different positions comprising an adjusting wheel fixed to a horizontal shaft mounted in the machine frame, said shaft having fixed thereto two indicator drums corresponding to the printing arms of the magazines and indicating which 55 of the arms that, at the moment, assumes a position right in front of its operative position, said shaft having also fixed thereto a toothed wheel meshing with another toothed wheel fast on one 60 end of a shaft mounted in the machine frame perpendicularly to the firstmentioned shaft, the lastmentioned shaft at its other end carrying another toothed wheel meshing with two toothed 65 racks located opposite one another and each being fixed to one of the magazines, the adjusting wheel consisting of an outer portion rigidly connected with an inner hub portion loosely mounted on the adjusting wheel shaft but adapted to be tightened against a collar on said shaft by means of a nut screwed on to the threaded end of the shaft.

3. In a ticket printing machine having a frame, 70 two vertically adjustable magazines each comprising a plurality of movable arm members, each of said arm members having a ticket printing plate fixed thereto, locking means for securing

ing said magazines in different vertical positions, means for selectively moving one arm member from either of said magazines at each locked position from a storage position inside the magazine to an operative position outside the magazine, and means for moving the magazines into said different positions comprising an adjusting wheel fixed to a horizontal shaft mounted in the machine frame, means for locking the wheel in adjusted position, said shaft having fixed thereto two indicator drums corresponding to the printing arms of the magazines and indicating which of the arms that, at the moment, assumes a position right in front of its operative position, said shaft having also fixed thereto a toothed wheel meshing with another toothed wheel fast on one end of a shaft mounted in the machine frame perpendicularly to the firstmentioned shaft, the lastmentioned shaft at its other end carrying another toothed wheel meshing with two toothed racks located opposite one another and each being fixed to one of the magazines, the adjusting wheel being provided with a member which, when actuated by hand, is adapted to cooperate with means for releasing the adjusting wheel from a locked position.

4. In a ticket printing machine having a frame, two vertically adjustable magazines each comprising a plurality of movable arm members, each of said arm members having a ticket printing plate fixed thereto, locking means for securing said magazines in different vertical positions, means for selectively moving one arm member from either of said magazines at each locked position from a storage position inside the magazine to an operative position outside the magazine, and means for moving the magazines into said different positions comprising an adjusting wheel fixed to a horizontal shaft mounted in the machine frame, said shaft having fixed thereto two indicator drums corresponding to the printing arms of the magazines and indicating which of the arms that, at the moment, assumes a position right in front of its operative position, said shaft having also fixed thereto a toothed wheel meshing with another toothed wheel fast on one end of a shaft mounted in the machine frame perpendicularly to the firstmentioned shaft, the lastmentioned shaft at its other end carrying another toothed wheel meshing with two toothed racks located opposite one another and each being fixed to one of the magazines, a ring resting in a groove in the adjusting wheel being adapted to cooperate with the outer ends of levers, the other ends of which engage with a collar on a sleeve displaceably but not turnably mounted on the adjusting wheel shaft, the opposite end of said sleeve carrying a disc provided with an upstanding recessed flange and actuated by a spring in a direction towards the adjusting wheel to cooperate with a pin fixed to the machine frame, the arrangement being such that when the said ring is unactuated the spring controlled disc is forced with one of its recesses to engage the pin fixed to the machine frame, while upon actuation of the ring the recessed disc is forced out of engagement with said pin.

5. In a ticket printing machine having a frame, two vertically adjustable magazines each comprising a plurality of movable arm members, each of said arm members having a ticket printing plate fixed thereto, locking means for securing said magazines in different vertical positions, means for selectively moving one arm member from either of said magazines at each locked

position from a storage position inside the magazine to an operative position outside the magazine, and means for moving the magazines into said different positions comprising an adjusting wheel fixed to a horizontal shaft mounted in the machine frame, said shaft having fixed thereto two indicator drums corresponding to the printing arms of the magazines and indicating which of the arms that, at the moment, assumes a position right in front of its operative position, said shaft having also fixed thereto a toothed wheel meshing with another toothed wheel fast on one end of a shaft mounted in the machine frame perpendicularly to the firstmentioned shaft, the lastmentioned shaft at its other end carrying another toothed wheel meshing with two toothed racks located opposite one another and each being fixed to one of the magazines, such counterbalancing of the magazines being hereby obtained that the one magazine moves upward at the downward movement of the other magazine and vice versa, means for fixing the magazines in the adjusted position, said means comprising cams mounted on a shaft parallel to the direction of motion of the magazines, said cams, at the turning of said shaft, being adapted to enter grooves in the frame of one of the magazines.

6. In a ticket printing machine as claimed in claim 1, means for locking each printing arm in its operative position, said means comprising a locking pin adapted to enter into an aperture in the printing arm when the latter assumes its operative position.

7. In a ticket printing machine, at least two magazines adapted to be adjusted to a plurality of positions, a mechanism for selecting one of the magazines, a plurality of arms provided in each of said magazines, each arm carrying a printing plate and being adapted to be brought into and out of an operative position in the machine, a stationary plate provided above the operative position of the printing plates, beneath the stationary plate a pressure table movable up and down by means of a cam cooperating with a roller mounted in the lower portion of the pressure table, the lower portion of the pressure table being formed as a slide guided in the machine frame, the said pressure table on moving upwards pressing a ticket strip against the printing plate at the moment assuming operative position, and a pin at the top of the pressure table adapted at the upward movement of the said table to enter an aperture in the printing arm at the moment assuming operative position and to lock the arm in this position during the printing operation.

8. In a ticket printing machine two vertically adjustable magazines, each of said magazines comprising a plurality of pivoted printing arms, each of said printing arms having a ticket printing plate fixed thereto, means for selectively bringing one of said printing arms at a time into a position for printing a ticket, said selecting means comprising an arm having a handle, said arm being pivotally mounted on a horizontal shaft member, a slide member displaceably mounted in the machine frame, and having an oblique slot, a link connecting said arm to said slide member, a pin engaged in said slot, said pin being secured to and laterally extending from a shaft, said shaft being mounted for longitudinal displacement in the machine frame and actuating means at the end of said shaft for moving

said printing arms into and out of operative position in the machine.

9. In a ticket printing machine two vertically adjustable magazines, each magazine comprising a plurality of printing arms and means for adjusting said magazines into different height positions, said adjusting means comprising an adjusting wheel fixed to a horizontal first shaft member mounted in the machine frame, said first shaft member having fixed thereto two indicator drums corresponding to the printing arms of each magazine and indicating which of said printing arms is at the moment situated in a position corresponding to its operative position, and mutual counterbalancing means between said magazines comprising a first toothed wheel fixed on said first shaft member and meshing with a second toothed wheel meshing with another toothed wheel, said last-mentioned toothed wheel secured to one end of a second shaft member, said shaft member being mounted in the machine frame at right angles to said first shaft member, said second shaft member at its other end carrying a third toothed wheel, said third wheel meshing with two toothed rack members, said rack members being located opposite one another and each being fixed to one of said magazines, such counterbalancing of said

25

magazines being thereby obtained that one magazine will be moved upwards when the other magazine is moved downwards and vice versa.

GUSTAV ROBERT AHLSTRAND.
KARL AKE LAGERKVIST.
